UNITED STATES PATENT OFFICE.

HERBERT L. JOHNSON, OF YARMOUTH, MAINE.

FINGER GRIP FOR VIOLIN BOWS.

Application filed March 31, 1922. Serial No. 548,343.

To all whom it may concern:

Be it known that I, HERBERT L. JOHNSON, a citizen of the United States, residing at Yarmouth, in the county of Cumberland and State of Maine, have invented a new and useful Finger Grip for Violin Bows, of which the following is a specification.

This invention relates to finger grips for violin bows and the object thereof is to provide a simple and efficient protector for violin bows to prevent wearing of the wood by the fingers and to insure the fingers and thumb being held in correct position.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a portion of the violin bow with one form of this improved finger grip shown applied.

Fig. 2 is an end elevation thereof, and Fig. 3 is a side elevation showing a slightly different form of the invention.

In the embodiment illustrated in Figs. 1 and 2, the finger grip 1 constituting this invention is composed of sheet metal preferably of aluminum and may be of any desired length being substantially cylindrical or octagonal in form to fit over the handle of the bow B. This finger grip 1 is provided at its front end with an upwardly and inwardly curved finger rest 2 designed to support the front finger of the user's hand. At one side edge of the grip is a forwardly

and inwardly inclined thumb rest 3 positioned to conveniently and comfortably support the user's thumb in proper position. 45 Attaching lugs 4 are formed between the thumb rest 3 and the finger rest 2 and have passing therethrough securing screws as is shown clearly in Figs. 1 and 3.

The rear end of the finger grip 1 shown 50 in Fig. 1 has a split band 5 designed to encircle the bow B to assist in securing the device thereon.

In Fig. 3 the grip 1^a is similar to that shown in the other figures except that instead of having a clamping band 5 at its rear end, it is equipped with an upturned curved hand rest 6.

This improved finger grip may be clamped around the bow B without in any way injuring it and in addition to holding the forefinger and thumb in proper position, prevents wear of the bow by the fingers.

I claim:

A finger grip for violin bows comprising a sheet metal longitudinally split sleeve to fit over the handle of the bow and provided at its front end with an upwardly and inwardly curved finger rest and at one side edge with a forwardly and inwardly inclined thumb rest, attaching lugs formed between the thumb rest and the finger rest and apertured to receive a fastening element, the rear end of said sleeve having a split band to encircle the bow and assist in securing 75 the device thereon.

In testimony that I claim the foregoing as my own, I have hereto affixed my signature in the presence of two witnesses.

HERBERT L. JOHNSON.

Witnesses:

CHARLES O. ROWE,
FRANK D. MCNEILL.
